3 Claims. (Cl. 179—171)

The invention relates to amplifier arrangements particularly for the amplification of broad frequency bands.

It is an object of the invention to provide an amplifier arrangement adapted for the uniform amplification of broad frequency bands for television and similar purposes. It is a further object to provide an amplifier connected with its input circuit to a television pick-up tube or a photo-electric cell, having an output with uniform amplification over the complete range of input signal frequencies.

It is known to use an amplifier in which the output resistor of the television pick-up tube has a larger value than would be required by the width of the frequency band to be amplified. This has the advantage that the input voltage of the amplifier is much larger than in the usual arrangements with the exception of the highest frequencies so that the amplifier is safe against hum and disturbing noise. Arrangements of this kind however have the drawback that the frequency response is not uniform and that it is necessary to amplify the higher frequencies more than the lower frequencies in order to obtain a uniform amplification over the entire range.

According to the invention a uniform amplification is obtained by means of a very simple arrangement. An element comprising a condenser and a resistor is arranged in the cathode circuit of an amplifier tube to the grid of which is applied the uncorrected input voltage. This element is so dimensioned that the resistor is bypassed by the condenser only for the highest frequencies so that for all medium and low frequencies below a critical value the amplification of this tube is determined by the comparatively large cathode resistor and is therefore low for these frequencies. The amplification is increased for high frequencies as a consequence of the capacitive by-pass of the cathode resistor. In such an arrangement the increase in amplification with increasing frequency is extremely gradual until the effective impedance of the condenser equals the internal impedance of the amplifier tube. For values of the effective impedance of the condenser smaller than the internal resistance, the amplification then increases rapidly with increasing frequency. In order to emphasize lower frequencies, it would then be necessary to make the condenser larger and thereby its impedance smaller with respect to the internal impedance of the tube, which would tend to decrease the over-all amplification of the tube.

According to the invention the increase of the 55 500 $\mu\mu$ F. A series arrangement consisting of the

effective amplification of an amplifier with single frequency is enhanced by providing means for making the voltage of the by-pass condenser substantially independent of the frequency within the limits of the frequency band to be transmitted. In order to produce such a voltage at the by-pass condenser a negative resistance element is placed in series with the condenser having approximately the same value as the internal resistance of the amplifier tube. For this purpose a small resistor is placed into the cathode lead of the subsequent amplifier tube and the by-pass condenser is connected to the end of the resistor connected to the cathode of this following tube. The resistor situated between the cathode of the subsequent tube and ground has the phase of a negative resistance in consequence of the phase reversal of the first tube and is so dimensioned that its voltage is equal to the drop of voltage at the cathode of the first tube. The by-pass condenser carries therefore a current increasing with the frequency. The anode current of the amplifier will therefore also increase with higher frequencies.

Other aspects of my invention will be apparent or will be specifically pointed out in the description forming a part of this specification, but I do not limit myself to the embodiment of the invention herein described, as various forms may be adopted within the scope of the claims.

30 The single figure of the drawing shows a circuit arrangement embodying the invention.

The figure of the drawing represents a circuit of the last stage and its preceding stage of a picture signal amplifier disposed in the camera of a 35 television pick-up tube. The picture signals amplified in a number of preamplifier stages (not shown) are applied by way of input lead 1 to the circuit. The input lead contains a condenser 2 of 50 $\mu\mu$ F and a grid resistor 3 connected to the 40 control grid 4 of an amplifier tube 5. The cathode circuit of tube 5 contains a fixed resistor 6 of 1 kOhm connected in series relation with an adjustable resistor 7 of 1 kOhm. The screen grid 8 of tube 5 is connected by way of a lead 9 to the 45 positive terminal of a source of potential indicated by the plus sign and by way of a condenser 10 of 16 $\mu\mu$ F to ground. The anode of tube 5 is connected to the anode resistor 11 and by way of a condenser 12 of 50 $\mu\mu$ F to the grid 14 of tube 15 50 and to the grid leak resistor 13 of this tube. The output of tube 15 is taken off from line 17 connected to the anode resistor 16 of this tube. The cathode of tube 15 is connected to the cathode of tube 18 by means of a by-pass condenser 18 of

condenser 18 and the cathode resistor 19 of 25 Ohms of tube 15 is connected in parallel relation to the cathode resistors 6 and 7 of tube 5.

In the operation of this arrangement picture signals are applied by way of the lead 1. The output current of tube 15 is in counterphase to the output current of tube 5 so that the voltage drop across the resistor 19 and therefore the cathode potential of tube 15 or the potential of the terminal of the condenser 18 connected thereto is in opposite phase to the voltage developed in the cathode circuit of tube 5 across resistors 6 and 7. The resistor 19 therefore has the effect of a negative resistance in relation to the cathode circuit of tube 5 and as previously mentioned the high frequencies are amplified to a higher degree than low frequencies. The adjustable resistor 7 in the cathode circuit of tube 5 enables an adjustment of the frequency limit above which the amplification is increased.

What I claim is:

1. A signal amplifying arrangement for uniform amplification of signals having a wide band of frequencies comprising an electron discharge tube having a cathode, a control grid, and an anode, an input circuit connected to said control grid for applying thereto signals to be amplified, an output circuit connected to said anode for developing uniformly amplified signals, a circuit connected to said cathode comprising a resistance element connected in parallel relation to a series combination of a capacitance element and an element capable of exhibiting a negative resistance in the order of the internal resistance of said tube.

2. A signal amplifying arrangement for uniform amplification of signals having a wide band

of frequencies comprising an electron discharge tube having a cathode, a control grid and an anode, an input circuit connected to said control grid for applying thereto signals to be amplified,

5 5 an output circuit connected to said anode for developing uniformly amplified signals, a resistance element connected to said cathode, a capacitance element connected in parallel relation to said resistance element, and means connected in 10 series relation with said capacitance element for maintaining the voltage developed across said capacitance element substantially independent of frequency over a predetermined frequency band.

3. A signal amplifying arrangement for uniform amplification of signals having a wide band of frequencies comprising a first electron discharge tube having a cathode, a control grid, and an anode, an input circuit connected to said control grid for applying thereto signals to be amplified, an output circuit connected to said anode for developing uniformly amplified signals, a resistance element connected to said cathode, a second electron discharge tube having a cathode, a control grid and an anode, an input circuit connected to said 20 control grid and coupled to said output circuit of said first tube, a resistance element connected to said cathode of said second discharge tube, a capacitance element connecting said cathodes, said last-named resistance element being so proportioned as to exhibit a negative resistance equal in magnitude to the internal resistance of said first discharge tube, and an output circuit connected to said anode of said second discharge tube for developing substantially uniformly amplified signals.

ULRICH KNICK.
